CORPORATION OF MASSACHUSETTS.

BOOT AND SHOE MANUFACTURE.

Application filed March 2, 1925. Serial No. 12,763.

The present invention, though having fields of more general usefulness, is more particularly related to the art of boot and shoe manufacture. From a more limited aspect, it relates to shoe uppers having French-cord binding strips folded around their edges, and to methods of making such uppers.

According to present-day practice, the binding strip, after it is sewed to the upper, and an adjacent portion of the upper, are coated with wet cement, after which the strip is folded around the edge of the sheet to which it is sewed, and the folded strip is pressed into contact with the sheet. The wet cement is objectionable. It has therefore been proposed to use dry-cemented strips that are sewed to the shoe upper in dry-cemented form, and to heat the dry cement to liquefy it during the folding and pressing operation. The dry cement has a tendency, however, to interfere with the sewing operation. The liquefied cement at intermediate portions of the strip, furthermore, tends to engage against the said edge of the sheet, interfering with proper folding.

An object of the invention, therefore, is to improve upon present-day practice, to the end of producing a better French-corded upper. Other objects will appear hereinafter and will be pointed out in the appended claims.

The invention will now be explained in connection with the accompanying drawings, in which Fig. 1 is a view of a shoe upper manufactured according to the present invention; Fig. 2 is a view illustrating a preferred method of manufacturing the improved binding strip of the present invention; Fig. 3 is a section of a shoe upper showing a binding strip sewed thereto, prior to the folding operation; Fig. 4 is a similar section showing the binding strip already folded, the section being taken upon the line 4-4 of Fig. 1, looking in the direction of the arrows, but being enlarged with respect to Fig. 1; and Fig. 5 is a section similar to Fig. 4 of a modification.

According to the present-day practice, a French-cord binding strip 2 is first sewed at

12, along the edge 8 of the two longitudinally disposed edges 8 and 26, to a face 10 of a shoe upper 6, along an edge 4 of the upper. The upper 6 may be constituted of leather, cloth, or any other desired material and the 55 binding strip may be constituted of cloth, silk, leather, and the like. The binding strip is usually a grosgrain, galloon or similar fabric having its edges 8 and 26 selvedged. It is sufficient to have the edge 8 alone 60 selvedged, the weaving of this selvedged edge preventing the strip from tearing away along the stitches 12. Resulting from the manner in which the sheet and the strip are sewed together, they are generally in more 65 or less close parallelism, as shown in Fig. 3. Wet cement is then applied to the other face 16 of the shoe upper, along the edge 4, and to the whole face 14 of the strip 2, after which the binding strip is folded around the secured-together edges 4 and 8 and pressed flat 70 into contact with the face 16 of the shoe upper. The binding strip is held in contact with the face 16 by the cement.

The use of the wet cement is a troublesome factor in shoe factories. It has therefore been proposed to dry-cement the whole face 14 of the strip 2 prior to the sewing operation. The objections to this proposal have already been explained. 75

According to the present invention, a portion only of the face 14 of the strip is dry-cemented. This portion extends from the free edge 26 of the strip to a point 18, Figs. 3 and 4, or a point 20, Fig. 5. It is thus possible for the sewing needle to pierce the uncemented portion of the strip between the edge 8 and the point 18 or the point 20. The point 18 has the advantage over the point 20 in that the cement is coated over a large 80 area of the strip. The disadvantage, however, is that, after the dry cement has been liquefied, portions of the strip near the point 18 tend to engage and stick to the edge 4 of the shoe upper, resisting the effort of the operator to pull the strip tightly around the edges 4 and 8. A baggy fold results. By having the portion of the strip between the points 18 and 20 uncoated, the tendency is 85 eliminated, as the edge 4 of the sheet engages

uncoated portions only of the strip between the edge 8 and the point 20.

The folding may be done by hand or by machine. In either case, it is well to heat the dry-cemented strip as a whole before commencing the folding operation. This may be effected in any desired way, as by placing the shoe upper, with binding strip attached, in an electric oven, at a mild temperature, until the dry cement has become softened or liquefied. It is not, however, essential to heat the whole strip at once, as it may be heated step by step, during the folding operation. In the latter event, it is considered better to heat the strip prior to the actual fold-pressing operation, as a cold fold presser will tend to cool, and therefore harden, the liquefied cement. The dry cement may be of the same color as the binding strip, to prevent undesirable effects in case the liquefied cement oozes through the binding strip during the fold-pressing operation.

The strip may be cemented in many different ways, all within the scope of the invention. The cement may, for example, be applied in the form of dry strips, that may be caused to adhere to the binding strip 2 under heat. It is preferred, however, to apply the dry cement in liquid form, as from a cement pot 22. A roll 24, the lower portion of which dips into the pot 22, is positively driven by well known mechanism (not shown). The strip is drawn over the roll, as illustrated in Fig. 2, becoming thus coated. As the strip leaves the roll 24, the cement hardens and dries, after which the now dry-cemented strip is rolled into reels 30. A folder 28 causes the strip to become longitudinally folded before it travels to the roll 24, so that the upper folded portion, as viewed in Fig. 2, does not contact with the roll 24 and, therefore, remains uncoated.

The reels 30 may be supplied direct to the shoe factories, thus confining the cement pots to the manufacturers of the strips, and eliminating them from the shoe factories.

The dry cement may be any well known adhesive backing, such as gums, Pará, etc. It will be understood that the invention is equally applicable to other articles than that which is herein chosen for purposes of illustration, and the elements of the article need not necessarily be of the relative dimensions shown. It may be desirable, for example, to fold an element of relatively large dimension over the edge of an element of relatively small dimension. For definiteness, all such elements that are to be folded will be referred to in the claims as the "strip" and the element about the edge of which the strip is to be folded will be referred to as the "sheet", though the adopted terminology may not be strictly applicable

to the specific article which may be under consideration.

The invention is not restricted to the exact embodiment that is illustrated and described herein, but modifications may be made by persons skilled in the art without departing from its spirit and scope, as defined in the appended claims.

What is claimed is:

1. As an article of manufacture, a sheet of material to one face of which, along an edge of the sheet, an edge of a strip is secured, the margin of the strip adjacent to the unsecured edge of the strip being dry-cemented, the margin of the strip adjacent to the secured edge of the strip not being cemented, the unsecured edge of the strip being folded around the secured-together edges and pressed into contact with the other face of the sheet.

2. The method of making shoe uppers which comprises coating with adhesive material one side of the strip throughout a portion of the width leaving the remaining portion of said side uncoated, sewing the uncoated margin to one face of the marginal portion of the upper, folding the strip over the edge of the upper, and causing the adhesive coated portion of the strip to adhere to the opposite face of the marginal portion of the upper.

3. The method of making shoe uppers which comprises coating with adhesive material one side of the strip throughout a portion of its width leaving the remaining portion of said side uncoated, sewing the uncoated margin to one face of the marginal portion of the upper, the coated portion being conditioned so as not to stick to surfaces with which it contacts during the stitching operation, folding the strip over the edge of the upper, and causing the adhesive coated portion of the strip to adhere to the opposite face of the marginal portion of the upper.

4. An article of manufacture comprising a sheet and a strip stitched together along juxtaposed edges and elsewhere held together by a stripe of cement confined to the unstitched width of the strip, the stripe of cement extending longitudinally of the strip at one side of the stitching.

5. An article of manufacture comprising a shoe upper, a strip coated with adhesive material along one margin and stitched to an edge of the upper along its uncoated margin, the strip being folded over the edge of the upper and secured to the opposite side of the upper by said material.

6. An elongate binding strip of the type to be secured along the edge of a sheet and then folded over the edge and then have its free margin cemented to the opposite side of the sheet, characterized in that a band of cement is applied to the margin of said

strip which is to be folded over the sheet before the strip is secured to the sheet and in that the margin of the strip which is to be first secured to the sheet is free from cement, whereby no cement need be brushed on the sheet after the two are secured together and whereby the securing of the first

edge of the strip to the sheet is not hindered by cement on that edge of the strip.

In testimony whereof, we have hereunto ¹⁰ subscribed our names.
